(57) **CLAIM**

The ornamental design for a portion of a connector, as shown and described.

DESCRIPTION

FIG. 1 is a rear perspective view of a portion of a connector showing our new design;

FIG. 2 is a rear view thereof;

FIG. 3 is a front view thereof;

FIG. 4 is a right side view thereof;

FIG. 5 is a left side view thereof;

FIG. 6 is a top plan view thereof; and,

FIG. 7 is a bottom plan view thereof.

The broken line showing of various regions in FIGS. 1-7 is for illustrative purposes only and forms no part of the claimed design.
